Edgar V. Veltro

UNITED STATES PATENT OFFICE.

DAVIS MARINSKY, OF NEW YORK, N. Y.

SHOE-SOLE PROTECTOR.

1,343,329.

Specification of Letters Patent. Patented June 15, 1920.

Application filed November 3, 1919. Serial No. 335,395.

To all whom it may concern:

Be it known that I, DAVIS MARINSKY, a citizen of the United States, and residing at New York, in the county of Bronx and 5 State of New York, have invented certain new and useful Improvements in Shoe-Sole Protectors, of which the following is a specification, such as will enable those skilled in the art to which it appertains to make and 10 use the same.

This invention relates to means for protecting the soles of shoes and particularly the points or ends of tapered shoes of the class now generally worn by women, and the 15 object thereof is to provide an improved device of this class which may be quickly and easily passed on over the pointed end of the shoe sole and secured thereto.

The invention is fully disclosed in the 20 following specification, of which the accompanying drawing forms a part, in which the separate parts of my improvement are designated by suitable reference characters in each of the views, and in which:—

25 Figure 1 is a side view showing my improved shoe sole protector and indicating the method of applying the same;

Fig. 2 a bottom plan view thereof;

Fig. 3 a top plan view of the protector 30 detached;

Fig. 4 a side view; and,

Fig. 5 another side view showing a modification.

In the accompanying drawing, I have indicated at *a* the toe portion of a lady's 35 shoe of modern style, said toe portion being tapered as indicated and, in the practice of my invention, I provide a protector *b* for the pointed end of the sole of this shoe.

The protector *b* is approximately triangular 40 in general form but the apex or pointed end *b*² thereof is rounded to correspond with the shape of the pointed end of the sole of the shoe, and said protector is made of sheet 45 metal and is composed of a base plate or portion *b*³, the toe portion of which is provided with a raised rim member *b*⁴ having an inwardly directed top flange *b*⁵, and said raised rim member *b*⁴ and the top 50 flange *b*⁵ thereof extend around said toe portion of the protector and about half-way along the sides thereof, as clearly indicated in Figs. 1, 3, 4 and 5 of the drawing.

The base plate or portion *b*³ is provided 55 centrally of the toe portion thereof with a circular aperture *b*⁶ with which communica-

cates a central longitudinal slot or opening *b*⁷, which opens backwardly and forms a recess in the base or bottom portion *b*³ and is intended to give slight elasticity to the 60 protector or to permit of a slight lateral movement of the side portions *b*⁸ thereof.

The side parts of the base plate or portion *b*³ are provided with upwardly directed teeth or prongs *b*⁹ formed from the 65 material thereof, and in the use of this device it is forced backwardly onto the toe of the sole of the shoe as indicated in the drawing, and in this operation the rim and flange members *b*⁴ and *b*⁵ overlap the toe 70 of the sole of the shoe, and the adjacent side edge portions thereof, as will be readily understood and aid in holding the protector on the sole, and the teeth or prongs *b*⁹ are also driven into the sole as indicated in 75 Figs. 1 and 4, and said teeth or prongs in connection with the flange and rim members *b*⁴ and *b*⁵ will securely hold the protector on the toe portion of the sole of the shoe, as will be readily understood. 80

In Fig. 5 I have shown a modification of the protector in which the central part of the rim member *b*⁴ is provided with a backwardly directed tooth or prong *b*¹⁰, which is formed from the material thereof and in 85 forcing or driving the protector onto the toe portion of the sole of the shoe, as hereinbefore described, this tooth or prong enters said toe portion of the sole of the shoe and aids in holding the protector thereon 90 as will be readily understood.

It is a well known fact that in the use of shoes of the class described, which are usually provided with high heels, the toe portion of the sole of the shoe is very quickly 95 worn away and this injures the shoe to such an extent as to make expensive repairs immediately necessary, if the shoe is not to be thrown away, and with my improvement these repairs may be quickly and easily 100 made by the owner of the shoe, or the protector or protectors may be applied in the first instance before the toe portion of the sole of the shoe is worn away, and thus prevent such operation or injury to the shoe. 105

It will be understood that these devices may be made up in different sizes and kept in stock by any shoe dealer, and in the operation of attaching the protector or protectors to a shoe, as described, the aperture *b*⁶ and the slot *b*⁷ which communicates therewith gives the side portions thereof 110

a slight elasticity, and this also adapts the device for use in connection with shoes, the toe portions of the soles of which are of slightly different transverse dimensions.

5 I also preferably provide the side portions b^8 , or the rim members b^4 thereof, with inwardly and forwardly directed prongs b^{11} which are adapted to engage the side edge portions of the sole to aid in securing the protector device to the sole. In placing the device on the sole and after it has been secured in position by the prongs b^9 , the prongs b^{11} may be forced inwardly or embedded into the sole of the shoe by a suitable punch or nail.

10 Having fully described my invention, what I claim as new and desire to secure by Letters Patent, is:—

15 1. A protector for the toe portions of the soles of shoes comprising a plate adapted to closely fit and conform with the toe portion of a shoe and provided with a rim which incloses a part of the edge portion of the sole, and prongs cut in said rim and 20 which are normally in the plane of said rim, and adapted to be pressed into and embedded in the edge portions of the sole of the shoe to securely hold the protector in connection therewith.

25 2. The herein described protector for the toe portions of the soles of shoes, said protector comprising a base plate fashioned to conform with the toe portion of the sole and provided with a raised rim and the side 30 portions of said rim being provided with forwardly directed prongs cut from the

material of said rim and lying normally in the plane of said rim and adapted to be pressed inwardly to embed the same in the edge portions of the sole after the protector has been placed thereon and to securely hold the protector in position against forward movement on the sole. 40

3. The herein described protector for the toe portions of the soles of shoes, said protector comprising a base plate fashioned to conform with the toe portion of the sole and provided with a raised rim having an inwardly directed flange, the base plate being cut out to form spring members, means 45 for securing the base plate, or the separate members thereof, to the sole of the shoe, the side portions of said rim being provided with forwardly directed V-shaped prongs normally in the plane of said rim and 50 adapted to be pressed inwardly to embed the same in the edge portions of the sole after the protector has been connected therewith and to securely hold the protector against forward movement on the sole, and 55 said rim being provided centrally thereof with an inwardly directed prong adapted to pass into the toe portion of the sole. 60

In testimony that I claim the foregoing as my invention I have signed my name, 65 in presence of the subscribing witnesses, this 31st day of October, 1919.

DAVIS MARINSKY.
